BRUSH FOR DENTURES

George E. Luce and William M. Sheets, Portland,
Oreg., assignors, by mesne assignments, to
William M. Sheets, Portland, Oreg.

Application December 20, 1938, Serial No. 246,836

1 Claim. (Cl. 15—167)

This invention relates generally to brushes, and particularly to a brush for dentures.

The main object of this invention is to construct a brush particularly adapted to the cleansing of dentures with a special regard to the gum engaging portion thereof.

The second object is to construct a brush of the class described having a pencil grip and being otherwise constructed so as to make it possible to hold the brush firmly in the hand even when the hand engaging portion of the brush is wet.

The third object is to construct a brush of the class described which will expedite the cleaning of a denture by making the point of contact between the brush and the denture easily visible at all times.

These and other objects are accomplished in the manner set forth in the following specification as illustrated in the accompanying drawing, in

which:

Fig. 1 is a perspective view of a preferred form of the device.

Fig. 2 is a fragmentary longitudinal section through the bristle supporting end of the brush showing the recess for the index finger.

Fig. 3 is a perspective view showing the manner of applying the brush to a denture.

Fig. 4 is a plan of the brush.

Fig. 5 is an end elevation of the brush.

Similar numerals refer to similar parts throughout the several views.

Referring in detail to the drawing, there is shown a handle 10 on one side of whose end 11 is disposed the laterally extending surface cleaning brush 12 whose bristles are preferably normal to the handle 10. On the extreme tip 13 of the handle 10 is disposed the channel cleaning brush 14 whose bristles are substantially parallel to the handle 10.

The end 11 is somewhat thicker than the handle 10 and has provided therein a curved recess 15 adapted to receive the tip 16 of the index finger 17.

It will be noted in Fig. 3 that the device is held as is a pen or pencil making it possible for the user to direct his movements with ample accuracy and at the same time making it possible to inspect the surface being brushed as much as 5 desired.

It will be understood that the brush 12 is used for cleaning the major portion of the denture and is similar to other brushes of this type which are now in common use. The novelty of the device 10 resides in the channel cleaning brush 14 which is sufficiently long and rigid to thoroughly cleanse the channels 18 without having any portion of the brush end 11 striking the denture with the possibility of injuring same. This constitutes one of 15 the major hazards in connection with the use of the ordinary lateral brush for this purpose.

Brushes have been constructed in the past in which the bristles are formed on the end of the brush. A good example of which is shown in the 20 patent of Lowd No. 158,099 wherein the bristles C are set in the end (a) of a tooth brush handle. This type of brush is not successful owing to the fact that the thrust on the brush is longitudinal 25 and no finger grip or stop is provided for limiting the movement of the fingers along the brush handle or for preventing the finger tip from slipping off of the handle laterally. It is to overcome these conditions that we have devised our brush.

We claim:

A brush of the class described consisting of an elongated straight handle having channel brushing bristles extending from one end thereof in parallelism with the length of said handle, the longitudinal axis of said handle being offset from the longitudinal axis of the channel brushing bristle head, the offset junction between said handle and said head having a recess formed therein adapted to receive the tip of the first finger during a channel brushing operation. 40
